UNITED STATES PATENT OFFICE.

CLESSIE L. CUMMINS, OF COLUMBUS, INDIANA.

OIL ENGINE.

Application filed September 5, 1925. Serial No. 54,715.

This invention relates to oil burning engines of the type wherein the fuel is exploded and burned by the heat of the air compressed by the piston within the combustion chamber of the cylinder. The principal object of my invention is to effect a more thorough atomization and vaporization of a charge of liquid fuel before the same is injected from a vaporizing chamber 10 into the combustion chamber of the engine by a plunger or the like. To this end, I deposit a charge of liquid fuel into circuitous, tortuous or broken passages between the vaporizing chamber and the combustion chamber so that when compressed air is formed from the combustion chamber, through the tortuous passages into the vaporizing chamber, it picks up, atomizes and vaporizes the liquid fuel, after which 20 a plunger in the vaporizing chamber is advanced to eject the dry gaseous mixture into the combustion space through the passages, the passages being tortuous or broken to effect a more thorough break-up atomization 25 and vaporization of the fuel.

With the above and incidental objects in view, the invention consists in certain novel features of construction and combination of parts, the essential elements whereof are described in detail hereinafter and illustrated in full in the accompanying drawings.

Of said drawings, Fig. 1 is a vertical fragmentary section taken through the upper end of a four cycle engine showing the preferred form of embodiment of my invention applied thereto, and Fig. 2 is a fragmentary section through an ejector embodying a modified form of my invention.

Fig. 1 shows, in section, the upper part 40 of the cylinder 6 and reciprocating piston 7 of a four-cycle engine, to which, for the purpose of illustration, I have shown the preferred form of embodiment of my invention applied. An air intake valve 8 and an exhaust valve 9 may be of any approved construction.

The fuel injector, in general, comprises a body member or plug 10, an ejecting plunger 11, operable in the central bore 11' 50 of the plug, a cup-shaped member 12 fitting over and about the lower end of the plug, a second cup-shaped member 13 of generally similar shape, fitting over the inner cup-shaped member 12, and a fuel inlet valve 14 mounted in a bore 15 in the plug. The lower end of the central bore 11' is closed

by the cup 12 so that when the plunger 11 is elevated or retracted to the position shown in Fig. 1, an atomizing or vaporizing chamber C is formed under the plunger. The 60 concave bottom of this chamber C, formed by the cup 12, is conical and of the same contour as the lower convex conical end of the plunger 11, to form a seat therefor. The under side of the end of the cup 12 is 65 cut away so that a cup-shaped space 16, having a flat central portion and an annular conical portion, is formed between the cups 12 and 13. A plurality of equally spaced ports or openings 17 are formed in the lower 70 end of the cup 12 and communicate with the space 16 near its upper rim. A plurality of equally spaced openings or ports 18 are formed in the cup 13 and at their upper ends open into the conical portion of 75 the space 16 but adjacent its flat bottom. Opening upwardly into the flat portion of the space 16 is a conduit 19 which extends downwardly in the cup 13 and then upwardly through the cups 12 and 13 and part of 80 the plug 10, to the lower end of the bore 15, the upper end of this conduit 19 being closed by the needle valve 14.

The modification shown in Fig. 2 is very similar to the preferred form and I have applied like reference numerals to the corresponding parts for the sake of convenience. The modified form differs from the preferred form in that the lower portion of the conduit 19 is formed in the cup 12, instead 85 of in the cup 13, and opens downwardly 90 into the flat portion of the space 16.

I have not shown in detail in the drawings the operating means for operating the ejecting plunger 11 and the fuel valve 14, as any 95 desired or approved form of devices may be used. The arms 21 and 22, shown diagrammatically in dotted lines, may be considered as forming parts of the operating mechanisms for the plunger and valve respectively. 100

The operation is as follows: During the suction stroke of the piston 7, air is drawn into the cylinder past the air valve 8. During this same stroke, the fuel valve 14 is elevated by its operating mechanism to 105 unseat its lower end and a charge of liquid fuel, forced either by gravity or by a pump or other suitable means, flows through the conduit 19 into the annular space 16 and the ports 17 and 18, this annular chamber and the ports being of just sufficient volume to 110 hold the entire charge of liquid fuel. This

charge of fuel, which is forced into the annular space 16 and the ports 17 and 18, has stood in the conduit 19 from the time it was deposited therein during the preceding suction stroke, so that each charge of fuel, when it is deposited in the annular space and ports 17 and 18, is already heated which makes it more easily and thoroughly vaporized, while the passage of the fuel through 10 the conduit 19 and into the annular space 16 and ports 17 and 18 serves to cool the projecting end of the injector and hence prevents it from getting so hot as to cause pre-ignition or to cause a deposit of carbon 15 thereon.

From the beginning of the period when the liquid charge is deposited in the lower end of the vaporizing chamber until after the beginning or near the initial part of the 20 compression stroke of the piston, I slowly elevate the plunger 11 from its lowermost position to the position shown in Fig. 1, so as to create a partial vacuum in the vaporizing chamber C for the purpose of preventing 25 the partial vacuum in the combustion chamber from causing any of the liquid fuel to drip or be drawn into the combustion chamber. It will also be noted that the lower outer ends of the ports 18 are reduced in size 30 so that these ends are very small in diameter, which also tends to hold the oil in the ports and prevent it from dripping into the combustion space. The plunger 11 is held in retracted position during the remainder of 35 the combustion stroke, and during such stroke part of the heated air, compressed in the combustion chamber and heated due to its compression, is forced through the ports 18, the annular chamber 16 and the ports 17 40 into the vaporizing chamber 16. These streams of highly compressed heated air rushing through the openings and chamber 16 pick up the heated oil and thoroughly mix, atomize and vaporize it in the vaporizing chamber. Near the beginning of the 45 power stroke of the piston, the plunger 11 is rapidly advanced or depressed until its lower end is seated and during this movement of the plunger the dry gaseous mixture 50 of fuel and air is forced under high pressure out of the vaporizing chamber C through the restricted communicating openings 17, 16 and 18 into the combustion chamber of the cylinder, where it ignites or explodes, 55 thereby greatly increasing the pressure in the combustion chamber and driving the piston downwardly.

The principal feature of my present 60 invention is depositing the liquid fuel in the broken or tortuous communicating passages between the vaporizing chamber C and the combustion space so that the fuel is more thoroughly and readily broken up and vaporized. The tortuous passages effect 65 sudden or violent changes in the directions

of movement of the fuel and air, when the liquid fuel is carried by the streams of air into the vaporizing chamber and when the gaseous mixture is driven from the vaporizing chamber into the combustion space, and the globules or particles of oil are driven against different surfaces with the result that they are shattered or pulverized into smaller bits or atoms, thus making the vaporization of the fuel more rapid and 75 thorough.

I do not intend to be confined to the precise structures shown and described as it is obvious that various modifications may be made without departing from the spirit of 80 my invention.

I claim:

1. In an oil engine, the combination of a cylinder and a piston operable therein, a fuel vaporizing and injecting device comprising a vaporizing chamber having tortuous restricted passages communicating with the combustion space of said cylinder, a plunger reciprocable in said vaporizing chamber, means for discharging liquid fuel 85 into said passages so that the fuel is heated, vaporized and mixed with the air forced from said combustion space through said passages onto said vaporizing chamber, and means for operating said plunger to eject 90 the gasified mixture of air and fuel from said vaporizing chamber through said tortuous passages into said combustion space. 95

2. In an oil engine, the combination of a cylinder and a piston operable therein, and a fuel vaporizing and injecting device comprising a vaporizing chamber having tortuous restricted passages communicating with the combustion space of said cylinder and of sufficient volume to hold the charge of liquid fuel, means for depositing the charge of liquid fuel into said passages, so that the fuel is heated, vaporized and mixed with the air forced from said combustion space through said passages into said vaporizing chamber, a plunger operable in said vaporizing chamber, and means for operating said plunger to eject the gasified mixture of air and fuel from said vaporizing chamber through said tortuous passages into said combustion space. 100 105 110 115

3. In an oil engine, the combination of a cylinder and a piston operable therein, and a fuel vaporizing and injecting device comprising a chamber having tortuous restricted passages communicating with the combustion space of said cylinder, means for discharging liquid fuel into said passages during the suction stroke of the engine so that the fuel is heated, vaporized and mixed with the air forced from said combustion space through said passages into said vaporizing chamber during the compression stroke, and means for retracting said plunger while the fuel is being deposited in 120 125 130

said tortuous passages and for advancing
said plunger during the combustion stroke
of the engine to eject said gasified mixture
of air and fuel from said chamber through
5 said tortuous passages into said combustion
space.

4. In an oil engine, the combination of a
cylinder and a piston operable therein, and
a fuel vaporizing and injecting device com-
10 prising a body with its lower end project-
ing into the combustion chamber and having
a vaporizing chamber, an annular space in
its lower end, passages extending from the
space to said chamber and passages out of
15 registry with the first mentioned passages
and extending from said space to the com-
bustion chamber, means for depositing a
charge of liquid fuel in said passages and
space, a plunger reciprocable in said vapor-
20 izing chamber, and means for retracting
and advancing said plunger so that when
the plunger is retracted air is forced from
the combustion chamber through said pas-
sages and space into said vaporizing cham-
25 ber and mixes with and vaporizes the liquid
fuel and for advancing said plunger to eject
the mixture and fuel from said vaporizing
chamber through said passages and annu-
lar space into the combustion chamber.

30 5. In an oil engine, the combination of a
cylinder and a piston operable therein, and
a fuel vaporizing and injecting device com-
prising a body with its lower end project-
ing into the combustion chamber of the cyl-
35 inder and having a vaporizing chamber, an
annular space in its lower end, ports extend-
ing from said space to said vaporizing
chamber, ports out of registry with the
first mentioned ports and extending from

said annular space to the combustion cham- 40
ber and a conduit opening upwardly into
the center of said oil space to deposit a
charge of oil therein and in said ports, a
plunger operable in said vaporizing cham-
ber, and means for retracting and advancing 45

said plunger so that when the plunger is
retracted heated compressed air is forced
from the combustion chamber through said
ports and space into said vaporizing cham-
ber to vaporize the fuel and when the 50
plunger is advanced the vaporized mixture
of air and fuel is forced from said vaporiz-
ing chamber through said ports and space
into the combustion chamber.

6. In an oil engine, the combination of a 55
cylinder, having a combustion chamber, and
a piston operable therein, and a fuel vapor-
izing and injecting device comprising a plug
having a vaporizing chamber therein, a cup
on the end of the plug and having ports, 60
a second cup fitting over the first cup and
having ports out of registry with the first
mentioned ports, the cups forming a space
between them with which the ports of both
cups communicate, a plunger in said vapor- 65
izing chamber, means for depositing a
charge of liquid fuel into said space and
ports so that compressed air forced from
the combustion chamber carries the liquid
fuel into the vaporizing chamber and vapor- 70
izes the same, and means for retracting said
plunger to permit the heated air to enter
the vaporizing chamber and for advancing
the plunger to eject all of the vaporized
mixture from said vaporizing chamber into 75
the combustion chamber.
